San Francisco, Calif., a Corporation of Cali-
fornia

Application April 14, 1933. Serial No. 47,786

Term of patent 14 years

To all whom it may concern:

Be it known that I, DAVID J. BOLTON, a citizen of the United States, residing at Monterey, county of Monterey, and State of California, have invented a new, original, and ornamental Design for a Merchant's Trading Stamp, of which the following is a specification; reference being had to the accompanying drawing, forming part thereof.

The figure is a face view of a merchant's trading stamp showing my new design.

I claim:

The ornamental design for a merchant's trading stamp substantially as shown.

DAVID J. BOLTON.
